CLAIM

The ornamental design for a cover window for display device, as shown and described.

DESCRIPTION

FIG. 1 is a front perspective view of the cover window for display device showing our new design;

FIG. 2 is a front view thereof;

FIG. 3 is a rear view thereof;

FIG. 4 is a left side view thereof with the right side view being a mirror image;

FIG. 5 is a top view thereof with the bottom view being a mirror image;

FIG. 6 is a rear perspective view thereof;

FIG. 7 is a partial cross-sectional view of the cover window for display device taken in the direction of line 7-7 in FIG. 2; and,

FIG. 8 is an enlarged detail view of region 8 in FIG. 5. The dot-dash broken lines are for the purpose of illustrating the boundaries of the enlarged detail view and the cross-sectional view, and form no part of the claimed design.
